UNITED STATES PATENT OFFICE.

MILFORD J. NEWHOUSE, OF ONEIDA, NEW YORK.

BURGLAR-ALARM.

SPECIFICATION forming part of Letters Patent No. 425,045, dated April 8, 1890.

Application filed June 3, 1889. Serial No. 313,000. (No model.)

To all whom it may concern:

Be it known that I, MILFORD J. NEWHOUSE, of Oneida, county of Madison, in the State of New York, a citizen of the United States, have 5 invented certain new and useful Improvements in Burglar-Alarms, of which the following is a specification, reference being had to the accompanying drawings, in which—

Figure 1 is a front plan view. Fig. 2 is a front 10 elevation of the same suspended. Fig. 3 is a transverse section on a line *x* *x*, Fig. 2. Fig. 4 is a like view on the line *y* *y*, Fig. 2.

My invention relates to burglar-alarms, and especially to those which are portable, adapted 15 to be carried in the pocket, and which can be readily attached to any door or window, and which operate to explode a cap, a fulminate, or other detonator.

The object of my invention is to produce 20 such a burglar-alarm.

My invention consists in the several novel features of construction and operation hereinafter described, and specifically set forth in the claim annexed.

25 It is constructed as follows: *A* is the body, of rectangular form, and grooved in one of its staves longitudinally for nearly its whole length, forming a shoulder 1 at the top of the groove. On either side adjacent to the lower 30 end are flanged pieces 2, projecting inwardly. At the top end I form an eye 3, in which I secure a cord 4, and 5 is a tack of either the form shown in the drawings or of any desired construction.

35 *B* is the male portion, consisting of a piece of metal of a form and size to fit the groove in the body *A*, fitting therein loosely, and provided at its upper end with a nipple 6, upon which I place a cap 7, or other detonator, 40 and terminating at its lower end with an enlargement or head 8.

It will be observed that the throw of the striking-piece *B* is substantially equal to the distance between the cap and the shoulder 1.

45 This device is suspended by inserting the point of the tack into the upper sash of a window or into the casing above the top of the door, so that whenever the door is opened

a short distance or either sash of a window is moved vertically a little ways the strain upon 50 the cord will pull out the tack, the implement will drop, and, striking either the floor or the window-sill upon the head 8, the concussion or momentum will drive the body *A* downward and will forcibly strike the shoulder 1 55 against the cap and explode it. It will be observed, also, that the tack 5, being provided with a point 9 and a shoulder 10, when the point is inserted it can only be inserted up to the shoulder, and that when a window, for 60 instance, is raised the sash-rail will encounter the outer arms 11 and will press against it as a lever, and, in conjunction with the shoulder 10, will withdraw the point of the tack.

I am aware of the tubular alarm patented to 65 H. T. Helmbold January 6, 1885, No. 310,421, in which a screw-plug must be removed to insert the detonator and then again screwed in; but that is not my invention, because my construction embodies no removable plug, but is 70 always open to permit the detonator to be placed upon the nipple.

What I claim is—

A burglar-alarm consisting of a rectangular body having an open longitudinal groove in 75 one face for nearly its whole length and provided with lips projecting along a portion of the edges of the groove when folded over and opening out through the lower end and terminating at the top with a shoulder, in combination with a bar retained in said groove by the lips turned over onto it and fitting loosely therein and having a head shouldered to engage with the upper end of the lips and provided with a nipple to receive a cap upon 85 the top of the head and having a weight upon the lower end of the bar larger than said groove, and means for suspending the body, as set forth.

In witness whereof I have hereunto set my 90 hand this 30th day of April, 1889.

MILFORD J. NEWHOUSE.

In presence of—

H. P. DENISON,
C. W. SMITH.
